A. B. DOWELL.
CONCRETE LINING FOR SHAFTS.
APPLICATION FILED OCT. 10, 1917.

1,275,874.

Patented Aug. 13, 1918.

UNITED STATES PATENT OFFICE.

ALLEN B. DOWELL, OF ST. LOUIS, MISSOURI.

CONCRETE LINING FOR SHAFTS.

1,275,874.

Specification of Letters Patent. Patented Aug. 13, 1918.

Application filed October 10, 1917. Serial No. 195,696.

To all whom it may concern:

Be it known that I, ALLEN B. DOWELL, a citizen of the United States, residing at St. Louis, Missouri, have invented a certain new and useful Improvement in Concrete Linings for Shafts, of which the following is a full, clear, and exact description, such as will enable others skilled in the art to which it appertains to make and use the same, reference being had to the accompanying drawings, forming part of this specification.

My invention relates to a lining particularly designed for the shafts of mines and like vertical excavation, although with incidental consequential changes, lining of my improved construction can be economically and advantageously used in subways, sewers, wells, cisterns, sunken tanks, silos, storage bins, or wherever a strong and substantial fire, water and rust-proof lining is desired.

The principal objects of my invention are, to provide a lining in the form of slabs of concrete, in order that said lining will be wholly fire, water, and rust-proof and not subject to rapid disintegration or decay, and further, to form the slabs of lining material so that their meeting ends will interengage by means of a series of offset joints and shoulders, thereby forming a comparatively strong and rigid structure which will readily withstand all internally and externally applied stresses which may be applied while the lining is in service.

A further object of my invention is to provide a lining material which can be easily and cheaply manufactured and assembled for use.

With the foregoing and other objects in view, my invention consists in certain novel features of construction and arrangement of parts, hereinafter more fully described and claimed, and illustrated in the accompanying drawings, in which—

Figure 1 is a perspective view of a short vertical section of lining, the same being constructed in accordance with my invention;

Figs. 2 and 3 are perspective views of the slab members utilized in my improved lining, and said slabs being shown inverted or upside down;

Fig. 4 is a perspective view of a corner of a lining structure of my improved construction;

Fig. 5 is a detail section through portions of two of the lining members and showing

the construction whereby an air, and water-proof joint is provided;

Fig. 6 is a detail view of a joint utilized between two members utilized in forming an oval or circular lining;

Fig. 7 is a detail section of a joint between members utilized in forming a polygonal lining.

As illustrated in the accompanying drawings, my improved lining is made in the form of slabs of any desired length, breadth and thickness, said slabs being constructed of concrete or analogous hardened plastic material and when the lining material is used for substantially square or rectangular shafts, two sets of slabs are provided, one set for the sides of the shaft and another set for the ends.

It will be understood that the slabs are laid in courses as illustrated in Fig. 1.

The members 10 forming the slabs used at the sides of the shaft are made by pouring plastic concrete into suitable forms and prior to the pouring operations, pairs of reinforcing bars 11 are located in the forms so that the resulting slab is reinforced. These bars are preferably spread apart throughout their central portions and their ends are brought together, thereby providing a construction which materially strengthens the completed slab.

The inner face of the slab 10 is cut away near both ends to form vertically disposed shoulders 12 and formed integral with both ends of each side slab 10 and at the bottoms thereof are outwardly projecting rectangular blocks 13. Formed in the underface of each slab 10 is a longitudinally disposed groove 14 which is substantially U-shape in cross section and which is adapted to receive a comparatively small body of cement when the slabs are laid one on top of the other, thus forming a bond between two slabs and providing an air and water tight construction at the joint.

The slabs 15 used at the ends of the lining structure are molded in suitable forms and embedded in said slabs are longitudinally disposed reinforcing bars 16, the central portions thereof being spaced apart from each other.

Formed integral with the ends of these slabs 15 and extending outwardly from the upper portions thereof are blocks 17, preferably rectangular in form and approximately the same size as the blocks 13 on the

- side slabs. Formed integral with the inner face of each slab 15 and adjacent to the ends thereof are vertically disposed ribs 18, the outer faces 19 of which occupy planes parallel with the planes occupied by the end faces of the slab 15 and said faces 19 being offset from the ends of the slab a distance equal to the depth of the shoulders 12 on the side slab 10.
- 10 Formed in the underside of each end slab 15 is a longitudinally disposed groove 20 which is adapted to receive a body of cement or the like when the slabs are properly assembled for use.
- 15 When the slabs thus constructed are utilized for forming a substantially rectangular lining for a shaft, they are laid in courses as illustrated in Fig. 1 with sufficient bonding material, preferably concrete, interposed between the rows to fill the grooves 14 and 20, and provide air and water tight joints.

20 The rectangular blocks 17 on the end slabs overlie the rectangular blocks 13 on the side slabs and the inner vertical corners of the ends slabs fit snugly against the vertical shoulders 12 on the ends of the side slabs. Portions of the inner faces of the side slabs immediately adjacent to the shoulders 12 bear directly against the faces 19 of the vertically disposed lugs 18 on the end slabs. Thus, the meeting ends of the slabs are united by vertically and horizontally disposed joints, the same being disposed so as to effectually resist all internally and externally applied stresses which may be applied while the lining is in service.

25 As illustrated in Fig. 1, vertically disposed angle bars 21 may be secured to the central portions of the side lining slabs, said angle bars serving as supports and points of attachment for transversely disposed rails 22, these latter dividing the space within the lining into two vertical shafts.

30 Secured at suitable points on the inner face of the end lining slabs are brackets or supports 23 for the vertically disposed cage guides.

35 When my improved lining is constructed for a circular or oval shaft, the joint between the ends of two of the slabs is constructed as illustrated in Fig. 6 and when the slabs are constructed for an angular shaft, the

40 joint between the meeting ends of two slabs is formed as illustrated in Fig. 7.

45 A lining of my improved construction can be easily and cheaply manufactured, is fire, water and dust-proof, is not subject to rapid disintegration or decay, and therefore, is particularly applicable for use as a lining for mine shafts, wells, cisterns, sunken tanks, 50 and likewise for subways, sewers and the like.

55 It will be readily understood that minor changes in the size, form and construction of the various parts of my improved lining can be made and substituted for those herein shown and described, without departing 60 from the spirit of my invention, the scope of which is set forth in the appended claim.

65 I claim:

70 The herein-described lining for shafts, which lining is laid in courses and each course comprising a pair of side slabs and a pair of end slabs, portions of each side slab on the inner face thereof being cut 75 away immediately adjacent to their ends to form vertically disposed shoulders which are inset with respect to the end faces of said side slabs, substantially rectangular blocks projecting outwardly from the lower 80 portions of the ends of each side slab, the upper faces of which blocks constitute horizontally disposed shoulders, and a pair of end slabs, the inner corners at the ends of which are adapted to bear against the vertically disposed inset shoulders, vertically disposed ribs formed integral with the inner 85 faces of the end slabs, the outer end faces of which ribs are inset with respect to the 90 end faces of said end slabs and which faces form vertically disposed shoulders which bear directly against the inner faces of the side slabs adjacent to the vertically disposed shoulders thereon, and substantially rectangular blocks projecting outwardly 95 from the upper portions of the ends of said end slabs, which last mentioned blocks are adapted to overlie the blocks projecting outwardly from the lower portions of the ends of the side slabs.

100 In testimony whereof I hereunto affix my signature this 2nd day of October, 1917.

ALLEN B. DOWELL.
